United States Patent Office.

CHARLES P. GORELY, OF BOSTON, MASSACHUSETTS.

Letters Patent No. 79,222, dated June 23, 1868.

IMPROVEMENT IN LETTER-BOXES.

The Schedule referred to in these Letters Patent and making part of the same.

TO ALL WHOM IT MAY CONCERN:

Be it known that I, CHARLES P. GORELY, of Boston, in the county of Suffolk, and State of Massachusetts, have invented an Improved Letter-Box; and I do hereby declare the following to be a full and correct description of the same, reference being had to the accompanying drawings, in which—

Figure 1 is a vertical section of a door-jamb having my improved letter-box applied, the operative mechanism being shown in side elevation.

This invention is an improvement on a letter-box invented by me, for which Letters Patent were issued, December 17, 1867; and it consists of a more simple device for connecting the lid or cover with the bell-wire, by the use of a series of pivoted bars, which serve not only to ring the bell, when the lid is opened, without interfering with the operation of the ordinary bell-pull, but operate to hold the lid firmly open when raised to the proper height, and to keep it securely closed when shut, all as hereinafter more fully set forth.

To enable others to make use of my invention, I will proceed to describe the construction and operation of my improved letter-box, referring to the drawing, whereon A marks the framing of an ordinary door-jamb, in which is cut a vertical slot or opening, J, of the usual and proper size for the reception of letters, papers, and ordinary mail-matter. A lid, B, is made to cover the slot, and is hinged at *a* to the door-jamb. This is opened by means of a knob, *b*. A small bracket, C, is attached to the inner side of the lid B, and to this is pivoted a rod, D, the other end of which is attached by a chaise-top joint, *d*, to a link, E, connected by a similar joint, *e*, to the short bar F, which is pivoted at *f* to a bracket fixed to the inside of the door-jamb. The pivot *e* is connected by wire and chain G to the spring S, which operates the door-bell, and this spring tends to draw the bar F downwards towards the pin P, to which the spring is attached. Chain H and wire *w* connect the bell-spring S with the ordinary bell-pull of the house-door, in the usual way.

The operation is as follows: When the lid B is closed, the various parts occupy the relative positions represented in black lines in the drawing. The position of the parts, when the lid is fully open, is represented in red lines. As the lid B is raised, the spring S continues to resist the rise of the arm F, until that arm has passed in front of a line drawn from P through the pivot *f*. When it has passed forward of that line, the spring tends to draw it down in front of that line, but the chaise-top joints are, in that position, brought to their bearings, and unite the three bars D, E, F, so as to form a rigid connection between the pivots *f* and *e*, thus firmly supporting the lid B in the elevated position shown in red lines in the drawing. When the lid B is depressed far enough to allow the arm F to pass back of the line P *f*, before mentioned, the spring S draws down the arm F, and forcibly and securely holds the lid B in the closed position. The introduction of the chains G H in the line of the bell-wires, in the manner shown, allows the spring S, and its attached bell, to be operated either by the ordinary bell-pull or by the lid B, without any interference between the two sources of motion.

Having thus fully described my invention, what I claim, and desire to secure by Letters Patent, is—

1. The combination and arrangement of the lid B, bars D, E, F, wire or chain G, and spring S, all constructed and operating substantially in the manner and for the purpose specified.

2. The introduction of the chains H and G into the length of the bell-wires, for the purpose of allowing either of two modes specified to be used in ringing the bell, without interfering with the other, as set forth.

The above specification of my said invention signed and witnessed at Boston, this 18th day of March, A. D. 1868.

CHAS. P. GORELY.
